Patented Oct. 31, 1967

209,120

ILLUMINABLE VANITY CASE OR SIMILAR ARTICLE

Harold Brickman, 5517 N. California Ave., Chicago, Ill.
60645, and Robert Deschamps, 1196 S. Main St., Lombard, Ill. 60148

Filed Oct. 22, 1965, Ser. No. 87,743

Term of patent 14 years

(Cl. D87—5)

Fig. 1

Fig. 2

Fig. 3

Fig. 4

Fig. 5

Fig. 6

Fig. 7

FIG. 1 is a front perspective view of an illuminable vanity case or similar article showing our new design, in closed condition;

FIG. 2 is a rear elevational view thereof;

FIG. 3 is a left-end elevational view thereof, the opposite end being a mirror image thereof;

FIG. 4 is a top plan view thereof;

FIG. 5 is a bottom plan view thereof;

FIG. 6 is a perspective view of the case in open condition, showing the grooming-implements compartment; and

FIG. 7 is a perspective view thereof showing the illuminable-mirror compartment of the case.

We claim:

The ornamental design for an illuminable vanity case or similar article, as shown and described.
